UNITED STATES PATENT OFFICE.

WILLIAM H. JOSSELYN, OF BRIDGEPORT, CONNECTICUT.

AUTOMATIC WATER-SIGNAL.

SPECIFICATION forming part of Letters Patent No. 361,824, dated April 26, 1887.

Application filed July 20, 1885. Serial No. 172,176. (No model.)

To all whom it may concern:

Be it known that I, WILLIAM H. JOSSELYN, a citizen of the United States, residing at Bridgeport, in the county of Fairfield and State of Connecticut, have invented certain new and useful Improvements in Automatic Water-Signals; and I do hereby declare the following to be a full, clear, and exact description of the invention, such as will enable others skilled in the art to which it appertains to make and use the same.

My invention has for its object to devise a simple and reliable method and apparatus for signaling from one end to the other of a hose or pipe filled with water, making use of the water itself as a means of communicating the signal, and it is especially valuable in connection with steam fire-engines, as it enables the men holding the nozzle of a line of hose to communicate instantly with the engineer when more or less pressure is desired.

It is of course well understood that the men holding the nozzle are more often than not out of sight and hearing of the engineer, and even if they were not out of sight, the distance from the engine and the noise would render it utterly impossible for the men holding the nozzle to communicate with the engineer with the voice.

Heretofore numerous experiments have been made, and numerous systems of signaling from the end of the hose to the engineer have been devised; but, owing to the rough usage to which the hose is necessarily subjected and to its great expansion and contraction under different circumstances, none of them have proved successful or been found worthy of adoption, so far as I am aware, and at the present time it is frequently necessary to send a man from the end of the line to the engineer when a change in pressure is required. In order to wholly do away with this serious evil I have devised the method of signaling which I will now describe, referring by letters to the accompanying drawings, forming part of this specification, in which—

Figure 1 is an elevation illustrating a simple and perfectly practical means of carrying out my improved method, the nozzle and the hose-connection at the opposite end being shown, the hose itself being broken away;

Fig. 2, an end elevation, looking from the left in Fig. 3, a gong being indicated in dotted lines; Fig. 3, a reversed side elevation of the metallic section or body which carries the operative parts, the hammer-spring being removed; Fig. 4, a plan view; Fig. 5, a cross-section on the line xx in Fig. 3; Fig. 6, a modification of my invention, showing the same principle made use of to produce a signal by a whistle instead of a gong or bell. Fig. 7 illustrates a modified form, in which the operating-plate is made in the form of a ring whose central opening is of the same diameter as the internal diameter of the hose instead of a disk, in the center of the body, as in the other form; and Fig. 8 illustrates another modification, in which the operating-plate is rigidly attached to a shaft, which is extended outside of the body and when rotated causes the signal to be given.

In Figs. 1, 2, 3, 4, and 5, A indicates the source of supply—for example, the reservoir of a steam fire-engine or a hydrant; B, the discharge; C, the engine cut-off; D, the hose; E, couplings; F, the nozzle; and G, the nozzle cut-off, all of which may be of any ordinary construction.

H is a metallic section or body having a female screw-thread to engage the discharge, and a male thread, (see dotted lines, Fig. 1,) by which the hose is attached. I is a standard upon the body, to which is secured a gong, K.

L is a bell-crank lever pivoted to the standard. The outer end of this lever is pivoted to a piston, M, which passes through a stuffing-box, N, upon the body and down into the body, for a purpose presently to be explained.

I' is an arm projecting outward from the standard, to which is pivoted another bell-crank lever, O, which carries the hammer O'.

L' is a dog pivoted to lever L.

L² is a pin upon lever L, which acts as a stop to limit the movement of the dog; and L³ is a spring attached to lever L, the free end of which bears against dog L', to return it to its normal position after the signal has been given.

P is a spring secured at opposite ends to lever O, and to the standard or to a pin projecting therefrom, as shown. The action of this spring is to draw the hammer against the gong. The operation of the ringing mechan-

ism forms no part of my present invention, and any ringing mechanism might be substituted in lieu of the one shown. In the present instance the dog engages the edge of lever O, so that as the piston is raised and lever L is turned upon its pivot, lever O is likewise turned at the same time, which carries the hammer away from the gong until a point is reached at which the dog slips over the edge of lever O. This allows spring P to draw the hammer against the gong. On the return movement the dog slides over the top of lever O until it reaches the edge, when spring L³ forces it to its normal position. As stated above, however, I make no claim to the special ringing mechanism, and any other style may be substituted, if preferred.

Q is the operating-plate having a horn, Q', at its forward end, which engages the lower end of the piston. This plate is pivoted to swing in chamber R within the body. This plate may be a disk, as shown in Figs. 2 and 5, and swing in the center of the chamber; or, if preferred, it may be made in the form of a ring, as shown in Fig. 7. The chamber is made of greater diameter than the hose, in order that plate Q may not offer any obstruction to the passage of the water. When the form shown in Figs. 2 and 5 is used, the relation between the width of the plate and the diameter of the chamber is such that the water is not obstructed. When the other form is used, the diameter of the opening in the ring may be equal to the diameter of the hose, or, if need be, greater.

The nozzle F is of ordinary construction, any style of shut-off being all that is required to complete the signal. The action of the water when let on at the engine or hydrant is to carry plate Q forward to the position shown in Fig. 5 and in dotted lines in Fig. 3.

Q² is a stop upon the operating-plate, which strikes against any solid portion of the device to prevent the plate from being carried too far forward. The plate is held in this position—that is, as far forward as the stop will permit—as long as the water continues to run through the hose; but as soon as the flow is cut off or seriously checked at the nozzle the direction of pressure is instantly changed and the operating-plate is forcibly thrown back to the position shown in Fig. 2. This forces the piston violently upward, and by means of the levers described or any equivalent means causes the hammer to strike a blow upon the gong.

L⁴ is a stop upon lever L, which strikes against the gong, thus acting to prevent the operating-plate from being carried back too far when the nozzle cut-off is operated.

It will of course be understood that any other simple form of stop may be substituted if preferred. The instant that the nozzle cut-off is opened the operating-plate resumes the position shown in Figs. 3 and 5. This action may be rapidly repeated as many times as may be desired, each backward movement of the operating-plate causing a blow upon the gong. I am thus enabled, by shutting off the water at

the nozzle, to strike a blow upon a gong upon the engine, and by opening and again shutting off to repeat the blow.

70

It will be seen that by causing one, two, three, or any number of blows to be struck upon the gong I am enabled to give as many different signals to the engineer as the exigencies of the service may require. The gist 75 of my invention lies in the discovery of the change in the direction of pressure that is caused by cutting off the discharge at the nozzle, no matter by what means it is accomplished, and in utilizing the water in the hose 80 or pipe as a means of communication with the engineer. It is of course not necessary that the signals should be made by a gong, as a whistle or other device may be substituted if preferred, or an inaudible signal may be used. 85

In Fig. 6 I have illustrated a similar device, in which the signal is made by a whistle, S.

The steam is furnished through a pipe, S', and the operating-rod S² is acted on directly by the dog upon bell-crank lever L without 90 the intervention of a second bell-crank lever.

In this form I have shown lever L as pivoted to a supplemental standard, L⁵, secured to the stuffing box or any suitable portion of the device. T in Fig. 5 is an additional spring, 95 which may or may not be used, as is deemed best, its action being to draw the piston down after it has been raised.

In Fig. 8 I have shown the operating-plate as made fast to a shaft, Q³, which extends 100 through the body and into the gong or bell, the rotary movement of the shaft being utilized to cause the signal instead of a piston, as in the other form. In this form the amount of friction is materially reduced, which under 105 certain circumstances renders it the preferable form.

It should be understood that the location of the signal mechanism has nothing to do with the principle of the invention, as it is obvious 110 that the signaling devices may be placed wherever it is most convenient for them to be seen or heard.

I have shown and described certain novel and practical means for carrying out my improved method, but I do not desire in any manner to limit myself to the means shown and described, as it is obvious that various other means for producing the signal may be devised which, while entirely different from 120 those shown, will be wholly within the principle of my invention.

Having thus described my invention, I claim—

1. The combination, with a water-hose having a cut-off at one end, of a metallic section at the other end having an operating-plate adapted to swing within it, a piston connected to said plate, and means—for example, a gong—and mechanism connecting the hammer with 125 the piston, whereby when the water is cut off at the nozzle a signal is given at the engine.

2. A water-hose having a cut-off at one end and a metallic section at the other end, in

130

combination with an operating-plate adapted to swing within said section, a piston connected to said plate and working in a stuffing-box, signal mechanism—for example, a gong—⁵ secured upon said section, and mechanism connecting the hammer of the gong with the piston, as and for the purpose set forth.

3. The hose, the nozzle cut-off, and metallic section H, in combination with an operating-¹⁰ plate provided with a central opening through which the water passes, a piston connected to said plate, and mechanism connecting the piston with signal mechanism, as the hammer of a gong, whereby each time the water is cut ¹⁵ off the operating-plate is caused to move backward and the gong is struck.

4. The combination, with a hose and a cut-off at one end thereof, of a metallic section at the other end having a plate pivoted within it ²⁰ arranged to swing forward under pressure of the water, and to instantly swing back to its other position when the water is cut off, and signal mechanism—for example, a gong.

5. The hose, the cut-off section H, and a signal, as a gong, in combination with the ²⁵ piston and mechanism connecting it with the hammer of the gong, the operating-plate, and stops L⁴ and Q², which hold the operating-plate against moving too far forward or backward.

6. Metallic section H, and operating-plate Q, adapted to swing within said section, in combination with a piston connected to said plate, spring T, which draws the plate down after it has been raised, and signal mechanism, as a gong, connected with said piston, substantially as and for the purpose set forth.

In testimony whereof I affix my signature in presence of two witnesses.

WILLIAM H. JOSSELYN.
